BUS BAR ASSEMBLY

William M. Scott, Jr., Philadelphia, Pa., assignor
to I-T-E Circuit Breaker Company, Philadelphia, Pa., a corporation of New Jersey

Application October 24, 1936, Serial No. 107,321

8 Claims. (Cl. 247—3)

My invention relates to bus bar assemblies of the type wherein a plurality of bus bars are supported by insulator units and has for an object the provision of a simple, rugged and inexpensive means of mounting the bus bars and insulator units with a minimum of auxiliary supporting structure.

It is a further object of my invention to provide an enclosed bus structure in which the enclosure, the insulator units and the bus bars are mutually self-supporting and which includes a bracket for bracing one or more of the bus bar assemblies against stresses of the type which the insulator units are not adapted to resist without possibility of failure, as by fracture of the insulator body.

Heretofore it has been common practice to support a plurality of insulator bus bar assemblies upon a separate frame constructed from a plurality of iron bars rigidly bolted together. The separate frame, besides being expensive, increases the space requirements for a given number of bus bar assemblies and complicates the problem of providing separate enclosures for each bus bar.

In carrying out my invention, in one form thereof I eliminate the provision of separate frames and the like, by utilizing the insulator units themselves, for supporting light-weight enclosures, for mutually supporting a plurality of bus bars, and for their normal function of electrically isolating each of the bus bars. The insulator units are protected from torsion or tensional stresses of damaging magnitude by provision of one or more brackets bolted or otherwise secured to the flanges of selected insulator units, the brackets having a configuration designed to withstand all stresses of tension, torsion, and the like, which tend to crack the porcelain or glass, or otherwise destroy the insulating properties of the insulators. The insulator units, preferably duplicate in form, are provided with duplicate flanges adapted to be secured together to form a rigid stack of insulator units and bus bars. Each bracket is designed for attachment to the inner side of any one of the insulator flanges in order not to interfere with the wall of an enclosure which may be clamped between adjacent insulator flanges.

For a more complete understanding of my invention, and for illustration of the forms it may take, reference is to be had to the accompanying drawings, in which:

Figure 1 is an enlarged fractional elevation,

partly in section, of a typical insulator bus bar assembly;

Fig. 2 is a perspective view, partly in section, of a bracket;

Fig. 3 illustrates, schematically, two vertical stacks of enclosed bus bar structure secured together by brackets, certain parts being omitted for sake of clarity;

Fig. 4 illustrates, schematically, a single vertical stack of enclosed bus bars with associated insulator units omitted for the sake of clarity;

Fig. 5 is a vertical elevation, partly in section, taken on the lines 5—5 of Fig. 6, of a stack of insulator bus bar assemblies with the housing of Fig. 6 omitted;

Fig. 6 is a vertical elevation, partly in section, taken on the lines 6—6 of Fig. 5, but including the enclosing housing;

Fig. 7 is an elevation, partly in section, illustrating a modified form of my invention as applied to bus bars the axes of which are normal to each other;

Fig. 8 is an elevation, partly in section, illustrating a further modification of my invention as applied to a horizontal stack of insulators;

Fig. 9 is a fractional plan view of a modified form of bracket; and

Fig. 10 is a perspective view of a coupling.

Referring to the drawings, I have shown my invention in one form as applied to a bus bar structure which may consist of a plurality of bus bars 10, 11 and 12, Figs. 5 and 6, supported one above the other by means of vertical stacks of insulator units spaced along the length of the respective bus bars, only one stack, comprising insulator units 13 to 18, being shown in the drawings. Each bus bar, formed of oppositely disposed channel-shaped conductors 19 and 20 interlocked by clamping devices 21, is mounted between opposing flanges of adjacent insulators. As shown in Fig. 1, each bus bar, as bus bar 10, is free to slide between the flanges 22 and 23 of insulators 13 and 14 respectively, by reason of four spacer sleeves 24 which provide clearance, as indicated at 25, above the bus bar. The respective ends of each spacer sleeve are threaded to receive cap screws 26 extending through openings provided in the respective flanges 22 and 23. The lower flange 27, Fig. 5, of insulator 13 is bolted or otherwise anchored to a support, as channel iron 28, supported by angle irons 29 secured, as by embedded bolts 30, to concrete supporting structure 31.

Between the flange 27 and the channel iron 28 is clamped the lower wall 32 of an enclosure

or housing, the upper opposing wall 33 of which is clamped between the flanges 34 and 35 of the insulator units 14 and 15. Cooperating with and secured to inturned ends of walls 32 and 33, Fig. 6, are side walls 36 and 37 which cooperate in a similar manner with downturned ends of the horizontal walls 38 and 39 clamped respectively between associated flanges of insulator units 16—17 and between flange 40 of insulator unit 18 and a channel iron 41. By removal of fastening screws 36a and 37a the panels or side walls 36 and 37 may be removed to permit access to each insulator stack. To support the upper end of the stack of insulators a pipe coupling assembly 42 is secured to a guide member 43 carried by a stationary supporting structure 44.

A proportionate share of the weight of the bus bars 10, 11 and 12 is carried by the stack of insulator units 13 to 18, inclusive, the remaining weight of the bus bars and enclosures being carried by the additional stacks of insulator assemblies (not shown) spaced along the lengths of the bus bars on opposite sides of the stack illustrated in Figs. 5 and 6. Since each bus bar upon expansion and contraction due to temperature change moves axially and at right angles with respect to the vertical axes of the respective stacks of insulator units, the resulting lateral forces on each stack tend to collapse the stack. These lateral forces place the insulator bodies, generally, and preferably formed of porcelain or the like, under bending stress and upon the occurrence of relatively large lateral forces there is likelihood of overstressing, cracking, or mechanical and electrical failure of the insulator units. Moreover, high magnetic forces, produced upon flow of large values of current, tend to move the bus bars toward or away from each other, thereby subjecting the insulator units to additional stresses. Because of the foregoing factors additional framework has heretofore been deemed necessary to protect the insulator units from failure.

In accordance with my invention I have found that the separate framework is rendered unnecessary by constructing the bus bar structure in the manner set forth above, particularly when supplemented by provision of brackets or braces 46 whose designs or configurations are particularly adapted to resist torsion, compression, tension, and bending and which are effective to prevent the application of unduly large torsional or tensional stresses to the insulator units. As shown in Figs. 1 and 2, each bracket 46, preferably formed of non-magnetic material, is provided with an arm 47 (preferably an extension of a side wall 48 of a body portion 49 of the bracket) the outer inturned end 47a of which is provided with an upwardly extending projection or pad 47b through the center of which is an opening 47c. Similar pads or projections 49b and 50b, with openings 49c and 50c therethrough, are provided on the body 49 of the bracket. The respective openings 47c, 49c and 50c are spaced for alignment with the openings through flanges 34 and 35, Fig. 1, through which the bolts 51 extend. The pads 47b, 49b and 50b are preferably machined accurately to position the bracket against the lower machined surface 34a of flange 34 so that when the nuts 51a of the respective bolts are tightened the bracket is fixed in a predetermined position; the body portion 49 is normal to the axis of bus bar 10 and is spaced slightly below the horizontal wall 33. By locating the body portion 49 below the wall 33 and by securing the in-

sulator ends of the brackets to the inner faces of the cooperating flanges, brackets may be secured to any of the flanges without changing the vertical dimensions of either the stack or housing. Additional pads or projections 53, with their outer surfaces in alignment with the outer face of the flange 34, bear against and form supports for the wall 33.

The bracket 46, though relatively light in weight, is exceptionally strong by reason of interconnecting side walls 48, 48a, an end wall 54, and an intermediate wall 49a. As shown in Fig. 1, the end wall 54 is provided with openings through which extend bolts 55 which, in cooperation with a brace 56 and a coupling 56a, tightly clamp between the opposed faces of the bracket and coupling 56a the downturned edge 33a of wall 33, and the vertical wall 36.

When two sets of bus bars extend parallel to each other, the stacks of insulator units may be interconnected by braces. As shown in Fig. 3, no additional supporting structure is provided for the respective stacks 58 and 59 which rest upon a foundation 31. By reason of the brackets 46 interconnected by braces 60, however, the respective stacks are mutually self-supporting. Each of the several bus bars are enclosed in separate compartments by the walls aforesaid which are preferably formed of relatively light weight metal. I have found that copper of low specific electrical resistivity has less tendency to absorb energy by virtue of eddy current losses than metals having higher resistivity. In any event, the thickness of the copper or other metal walls need not be large since the insulator units and brackets carry all of the weight of the structure and absorb all of the stresses.

In one commercial embodiment of my invention each bus bar was designed to carry continuously 4000 amperes at 23,000 volts. Under short circuit or excessive overload conditions substantial magnetic forces of attraction or repulsion are exerted upon the bus bars but the bus bar assemblies described above are entirely satisfactory to take care of all abnormal conditions and current values many times the normal rating.

In cases where a single stack, Fig. 4, of insulator units is disposed near a wall 61, a brace 62 extending therefrom may be secured to bracket 46.

To remove one of the insulator units, by removal of panels or walls 36 or between adjacent brackets by removal of a section or panel of wall 37, access may be had to the bolts extending through the respective flanges of the insulator units. For example, Fig. 1, after the bolts 51 and cap screws 26 have been removed, the insulator unit 14 may be moved outwardly away from the associated insulator-end of bracket 46 which partially encircles the insulator flange. During this movement the insulator slides along the bus bar. As soon as it is clear of the bracket, the insulator may then be moved free of the bus bar 10 and removed from its compartment. The insulator unit 14, or a replacement unit, may be returned to the stack by carrying out the foregoing steps in the reverse order. Since the remaining units 13, 15 and 18, the housing, and the bus bars, are not disturbed, the described construction minimizes time for inspection and maintenance of the bus bar assembly as a whole.

Referring to the modification of my invention shown in Fig. 7, a vertical stack 58 of insulator units is interconnected with a horizontal stack 65 by means of the brackets 46 and 46', the bracket 46' being rotated through ninety degrees

with respect to the bracket 46. Since the openings, through which the bolts 67 extend, are located at the respective corners of a square, the brackets are interchangeable for use with both vertical and horizontally extending stacks; that is, each bracket may occupy four separate positions without change in the number of bolt-receiving openings.

Referring to Fig. 8, if a single horizontal stack 10 69 of insulator units is to be used, the brackets 70 and 71 are suitably secured to supporting structure 72. In this case, the brackets form the sole support for the entire assembly, including the housing forming the individual bus bar compartments.

In some cases where the insulator flanges are square, or where narrow rectangular flanges are mounted with the wide side of the rectangle facing the supporting structure, bracket 46a, Fig. 9, 20 may be provided with U-shaped open ends 73 and 74 in place of the hook-shaped ends 47, 47a of Fig. 1. Regardless of the shape of the insulator flange F, the spacing of the bolt holes may be such that either type of bracket may be used so long 25 as each insulator may be removed from the assembly without disturbing the bracket or other supporting structure.

Summarizing, in accordance with my invention, stacks of insulator units or bus bar assemblies 30 may be constructed from duplicate parts for horizontal or vertically extending bus bars; separate frame structure is unnecessary and individual insulator units may be readily removed from an assembly without disturbing the remaining units. 35 Stresses on the insulator bodies are kept within safe limits by the provision of the supporting and bracing brackets which may act as braces and/or cantilever supports for each assembly.

While I have shown particular embodiments 40 of my invention, it will be understood, of course, that I do not wish to be limited thereto since many modifications may be made, and I, therefore, contemplate by the appended claims to cover any such modifications as fall within the true spirit 45 and scope of my invention.

I claim:

1. A bus bar assembly comprising an insulator provided with flanges secured to opposite ends thereof, a bracket, one end of which, of relatively 50 small cross-sectional area, is adapted for engagement with one of said flanges at at least three points, means for rigidly securing said bracket to said flange at said three points, said bracket having a gradually increasing cross-sectional area 55 from its said end to its opposite end, and mounting means including means for rigidly fixing said opposite end of said bracket whereby said bracket minimizes application to said insulator of substantially all stresses other than stresses of compression.

2. A bus bar assembly comprising insulators provided with flanges rigidly secured to opposite ends thereof, a rigid support for one of said flanges of one insulator, bus bar mounting means secured to the opposite flange of said one insulator, a flange of a second of said insulators being secured to said bus bar mounting means, the opposing flange of said second insulator cooperating with the flange of a third insulator, walls 65 interposed between and lying flat against the faces of the respective flanges remote from said bus bar, side walls cooperating with said first-mentioned walls to enclose on four sides the bus bar, a bracket disposed between said first-mentioned 70 walls, one end of said bracket being secured to

the insulator side of one of said flanges and adjacent one of said walls, the opposite end of said bracket having a portion extending parallel to one of said side walls, and supporting means on the outside of said side wall for clamping said side wall therebetween in fixed position and for rigidly supporting said bracket. 5

3. In a bus bar structure, a bus bar, a pair of insulators each having two attachment flanges, 10 said insulators being axially aligned and secured to opposite sides of said bus bar, the combination of a bracket extending at right angles to the axis of said insulators and secured at one end to other structure and at its other end directly to one of said flanges for preventing lateral or angular movement thereof, all parts of said bracket lying between the outer planes of said two flanges of one of said insulators, said insulators being individually removable from said structure by movement normal to the longitudinal axis of said 15 bracket. 20

4. In a bus bar assembly including an insulator and its associated end flange, the combination of a bracket, one end, of relatively small cross-sectional area, of which is provided with 25 raised portions for cooperation with said flange on the insulator side thereof, said raised portions spacing said bracket below the end surface of said flange, the opposite end of said bracket having raised portions, the upper surfaces of which 30 are aligned with respect to said end surface of said flange, said bracket increasing in cross-sectional area from its end associated with said flange to its opposite end and there terminating in a portion arranged parallel to the axis of said 35 insulator and flange.

5. In a bus bar structure including, a bus bar, an insulator having attachment flanges at opposite ends thereof, a plurality of bolts passing through one of said flanges for maintaining fixed 40 the relative positions of said bar and said insulators, the other flange of said insulator secured to an attachment flange of a second insulator having similar flanges, the combination of a rigid member secured to the adjacent flanges of said 45 insulators by bolts passing through the two flanges and the member, one of said flanges lying between said member and said other flange, said member encompassing one of said insulators at least half its circumference to support same, said 50 insulator being removable from said member without axial movement upon removal of the bolts from both its flanges.

6. In a structure comprising a plurality of bus bars disposed in a common plane, insulating 55 means, symmetrical about a given axis, for spacing said bars, said means having a flange substantially midway of adjacent bars, the combination of a rigid member secured to said flange one end of said member embracing at least half 60 the circumference of said insulating means without changing the spacing between said bus bars, said member extending at right angles to the axis of said insulating means, and means for securing the opposite end of said rigid member 65 to other structure, said insulating means being removable from said first-mentioned end of said member in a direction normal to the axis of said insulating means without movement of other parts of said structure. 70

7. In combination, a bus bar assembly comprising an insulator having a flange at each end thereof, a bus bar secured to one of said flanges, an enclosure for said bus bar and said insulator comprising end-wall elements of sheet material 75

one of which is secured to the insulator flange-face remote from said bus bar and side-wall elements secured to said end walls, a bracket wholly within said enclosure and disposed in supporting relation to at least one end and one side wall of said enclosure, means for securing one end of said bracket to the insulator side of said insulator flange remote from said bus bar and adjacent one of said end walls, and means securing the other end of said bracket, a side wall, and an end wall of said enclosure, to rigid structure outside of said enclosure.

8. The combination with an assembly comprising

ing a plurality of rigid conductors having their axes parallel and lying in the same plane, a column of insulating units rigidly spacing said conductors, and an enclosure for each of said conductors supported by said insulating units, of supporting structure external to said assembly, a bracket, and means for securing said bracket to any one of said insulating units intermediate the ends thereof and to said external supporting structure for supporting said bus bar structure in a direction normal to said plane and for positioning said assembly.

WILLIAM M. SCOTT, JR.
